(57) **CLAIM**

I claim, the ornamental design for a luminaire, as shown and described.

DESCRIPTION

FIG. 1 is a first side elevation view of the invention;
FIG. 2 is a second side elevation view of the embodiment of
FIG. 1;

FIG. 3 is a bottom plan view of the embodiment of FIG. 1;
FIG. 4 is a top plan view of the embodiment of FIG. 1;
FIG. 5 is a top perspective view of the embodiment of FIG. 1;
and,
FIG. 6 is a bottom perspective view of the embodiment of
FIG. 1.

The degree of transparency or opaqueness of the lens of the
luminaire forms no part of the claimed design.

The phantom lines shown in FIG. 1–FIG. 6 are environmental
and not part of the claimed design.

References to “side”, “top”, “front” and “bottom” in the
figure descriptions are not meant to require certain in-use orientation;
a luminaire according to the claimed design may be
used in any orientation.
